UNITED STATES PATENT OFFICE.

WALTER BUDDS, OF CHICAGO, ILLINOIS.

CIGAR LIGHTER.

Application filed April 29, 1926. Serial No. 105,604.

My invention relates to cigar lighters and has among its other objects the production of devices of the kind described which are neat and attractive in appearance, convenient, 5 efficient and satisfactory for use wherever found applicable.

A particular object of the invention is to provide a portable cigar lighter which may be positioned upon the floor beside a chair or 10 the like and which will be of the right height for the occupant of the chair.

Another particular object of the invention is to provide an improved cigar lighter of the kind described which will automatically be 15 come functionally operative when the user brings it to the cigar.

One form of the invention is embodied in a cigar lighter which comprises a portable lamp, or stand, carrying a reel around which 20 suitable electrical conductors are wound, a spring being provided for automatically winding the conductors around the reel. The conductors are connected to any suitable 25 source of electrical energy through brushes carried by the reel and they connect with a resistance element in the lighter through a switch which will close the circuit when the conductors are subjected to tension.

Many other objects and advantages of the 30 construction herein shown and described will be obvious to those skilled in the art from the disclosure herein given.

To this end my invention consists in the novel construction, arrangement and combination of parts herein shown and described, 35 and more particularly pointed out in the claims.

In the drawing, wherein like reference 40 characters indicate like or corresponding parts;

Fig. 1 is an elevation of a device embodying the invention;

Fig. 2 is a fragmentary vertical section taken through a portion of the device shown 45 in Fig. 1;

Fig. 3 is a section taken on line 3-3 of Fig. 2;

Fig. 4 is a section taken on line 4-4 of Fig. 2; and

Fig. 5 is a central longitudinal section taken through the resistance element and the handle therefor.

Referring to the drawings wherein I have shown a preferred form of the invention embodied in a device, the reference character 10 designates in general a floor lamp or stand,

comprising a suitable base 11. In the illustrated embodiment of the invention, the stand 10 is provided with electrical fixtures 12 but it will be understood as this description progresses that some features of the invention are not limited to such fixtures but may be embodied in any suitable stand which is portable and may be positioned beside a chair, a table or the like.

As best illustrated in Fig. 1, the stand 10 comprises a substantially vertical tubular post 15 which is enlarged at 16 to provide a chamber 17, a reel 18 and other mechanism being positioned in said chamber. The reel 18 is preferably rotatably journaled upon a pin or rod 19, the ends of which are screw-threaded into wedge-shaped blocks 20, one end of the rod 19 being provided with left-hand screw threads and the other end thereof 75 being provided with right-hand screw threads. Obviously, the rod 19 may be rotated to wedge the blocks 20 against the inner surface of the tubular member 15.

Wound around the reel 18 is a cable 22 comprising a plurality of electrical conductors 23 and 24 (see Fig. 5), the electrical conductors 23 and 24 being connected to metallic rings 25 and 26, respectively, carried by the reel 18. In the illustrated embodiment of the invention the reel 18 is formed from any suitable electrical insulation, but it is readily understood that the reel 18 may be formed of metal, if so desired, and that the rings 25 and 26 may be insulated from each other and the 80 metal. Engaging the rings 25 and 26 are brushes 27 and 28, respectively, mounted upon a block 29 which is formed from any suitable electrical insulation and is carried by the rod 19. As shown, the block 29 is adjustably 85 mounted upon the rod 19, nuts 30 being provided for this purpose. The brushes 27 and 28 are preferably secured to the block 29 by screws 32 and 33, respectively, which also serve as binding posts so that the brushes 27 and 28 may be connected by electrical conductors 35 and 36, respectively, to any suitable source (not shown) of electrical energy.

It will be noted that conductors 37 and 38 are also connected to the binding posts 32 and 33, 90 respectively, to connect the electrical fixtures 12 with the source (not shown) of electrical energy.

Positioned adjacent the reel 18 is a spiral spring 40 which has its inner end secured to a collar 41, the collar 41 being pinned to the rod 19 and being adapted to cooperate with

a collar 43 to prevent longitudinal displacement of the reel 18 along the rod 19. The outer end of the spiral spring 40 is fixed to the reel 18 by a screw 44 or the equivalent. 5 The construction is such that the spring 40 tends to wind the cable 22 around the reel when the spring is under tension.

Referring now to Fig. 5, it will be noted that the conductor 24 is fixed to one end of 10 a switch element 46 which is pivotally mounted intermediate its ends by a pin 47, the switch element being disposed in a hollow handle 48 which is preferably formed of any suitable electrical insulation. A tension 15 spring 50 yieldingly holds the switch element 46 in a position wherein it does not engage a contact 52 mounted within the handle 48, the contact 52 being connected with one terminal of a resistance element 53 embedded or 20 otherwise mounted upon a plate 54 of any suitable electrical insulation. The other end of the resistance element 53 is connected to the conductor 23. If the cable 22 is unwound or withdrawn from the reel 18 against the 25 action of the spiral spring 40 the tension under which the conductor 24 is placed will cause it to angularly displace the switch element 46 into a position wherein the switch element engages the contact member 52. Electrical 30 current will then flow as follows: from the source of electrical energy through the conductor 35, the contact 27, the ring 25, the conductor 23, the resistance 53, the contact 52, the switch element 46, the conductor 24, the 35 ring 26, the brush 28 and back through the conductor 36 to the source of electrical energy.

In the preferred embodiment of the invention, the enlarged portion 16 of the tubular post 15 is formed in the post at a height 40 which will bring the cigar lighter into a convenient position for the occupant of a chair or the like adjacent which the stand is placed. An aperture 56 which is formed in the tubular post 15 and through which the cable 22 is drawn when it is being unwound from the reel is preferably of sufficient size that the handle 48 may be inserted therein, the handle being preferably provided with an enlarged 45 head 57 which prevents the handle from dropping into the post. The spiral spring 40 is preferably so designed that when the handle 48 is positioned in the aperture 56 the conductors 23 and 24 will not be under tension. 50 It will be apparent that when the holder 48 is positioned within the aperture 56, the tension of the spring 40 is practically exhausted so that the tension of the spring 50 will move the switch element 46 upon its pivot and disengage the same from the contact 52.

While I have shown the stand 10 as part of a portable lamp, it is to be understood that I am not limited to such construction as that part of the post 15 disposed above the en-

larged portion 10 thereof may be omitted from the construction if it is so desired. However, I find that the post of a portable lamp forms a convenient place in which to mount the reel 18 and the elements associated therewith.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

1. A cigar lighter comprising a resistance element, a plurality of conductors for connecting said resistance element to a source of electrical energy, and a switch operable by tension to which one of said conductors is subjected for closing an electrical circuit through the resistance element.

2. A cigar lighter comprising a resistance element, a switch element, a contact engageable by said switch element, a conductor connecting said contact to one terminal of said resistance element, a conductor connecting the other terminal of said resistance element to a source of electrical energy, a spring for holding said switch element disengaged from said contact, and a conductor for connecting said switch element to said source of electrical energy, said last-mentioned conductor being adapted to bring said switch element into engagement with said contact when it is tensioned.

3. A cigar lighter comprising a switch element, a contact to be engaged by the switch element, means connecting the contact with a source of electrical energy, a spring for holding said switch element disengaged from said contact, and a conductor for connecting said switch element to said source of electrical energy, said last-mentioned conductor being adapted to move said switch element into engagement with said contact when it is tensioned.

4. The combination in a cigar lighter comprising a casing, of a pivoted switch member disposed therein, a contact member adjacent said switch member, a resistance element, a conductor joining said resistance element and said contact member, and another conductor connected to said resistance element, a spring for normally maintaining said switch member out of engagement with said contact member, and a conductor connected to said switch member and adapted to move the same into engagement with said contact member when said conductor is tensioned.

In testimony whereof, I have hereunto signed my name.

WALTER BUDDS.
